UNITED STATES PATENT OFFICE

2,684,700

RESILIENT PARALLEL JAW CLAMP

Reginald Bain, Phoenix, Ariz.

Application October 6, 1950, Serial No. 188,775

3 Claims. (Cl. 144—303)

1

This invention relates to clamps adapted to hold a plurality of superimposed elements in contiguity to one another and, more particularly, to a clamp adapted to be utilized in maintaining a plurality of elements in superimposed relationship to permit the simultaneous operation of a tool thereupon.

In describing the construction and mode of operation of a clamp constructed in accordance with my invention, it is illustrated as utilized in conjunction with a conventional bandsaw but it is obvious that the clamp can be utilized with any one of a plurality of different types of tools.

Conventional clamps of the type under consideration usually consist of a first clamping member which is secured to a second clamping member by adjustment means adapted to permit the adjustment of the first and second clamping members toward and away from each other. Such clamps cannot be readily used in conjunction with conventional machine tools, such as bandsaws and drill presses, because the second clamping member thereof is of such thickness that, when the clamp and the elements maintained in superimposed relationship therein are placed upon the table of the tool to be utilized, the thickness of the second clamping member causes the sides of the elements secured in the clamp to be disposed a substantial distance above the surface of the table of the tool while the opposite sides of the superimposed elements contact the surface of the table to incline the vertical axes of the superimposed elements angularly from a vertical axis normal to the plane of the table.

Therefore, when an attempt is made to make simultaneous cuts or to simultaneously drill holes in the superimposed elements, the cuts or holes are made at angles which are parallel to the angularly displaced axes of the superimposed elements from the vertical axis normal to the plane of the table.

It is, therefore, a primary object of my invention to provide a clamp for maintaining a plurality of superimposed elements in operative relationship with one another which is so constructed that when the clamp is disposed upon the table of a machine tool the vertical axes of the superimposed elements are maintained substantially parallel to an axis which is perpendicular to the surface of the table of the tool.

An additional object of my invention is the provision of a clamp for maintaining a plurality of separate articles in superimposed relationship with one another which includes a first clamping member and a second clamping member ad-

2

justably connected to said first clamping member to facilitate the adjustment of said first and second clamping members toward and away from each other, said second clamping member being so thin as to prevent the substantial inclination of the vertical axes of the articles from an axis perpendicular to the plane of a work table upon which the clamp and the articles are placed.

A further object of my invention is the provision of a clamp of the aforementioned type in which the second clamping member is formed of material of very light gage, said second clamping member being, therefore, deformable and dependent upon the surface of the table upon which it is imposed to prevent the undue deformation thereof.

An additional object of my invention is the provision of a clamp of the aforementioned type which includes a first clamping member and a second clamping member so thin as to prevent the substantial inclination of the vertical axes of articles disposed between said clamping members from an axis perpendicular to the plane of the table upon which the clamp and articles are placed and which includes a rigid block connected to the upper surface of said second clamping member to facilitate the attachment to said second clamping member of adjustment means connecting it to said first clamping member.

A further object of my invention is the provision of adjustment means adapted to maintain the first and second clamping members of said clamp in substantial parallelism with each other and to prevent any misalignment between said members which would result in the release of articles maintained between said members.

Other objects and advantages of my invention will be apparent from the following specification and the accompanying drawing, which is for the purpose of illustration only, and in which:

Fig. 1 is a vertical, partly sectional view of a clamp constructed in accordance with my invention;

Fig. 2 is an isometric view of a conventional bandsaw showing the manner in which a clamp constructed in accordance with my invention can be placed upon the table thereof without substantial deviation of the vertical axes of the superimposed articles in said clamp from an axis perpendicular to the surface of the table of the bandsaw;

Fig. 3 is a top plan view of the clamp; and

Fig. 4 is a transverse, partly sectional view taken on the broken line 4—4 of Fig. 1.

Referring to the drawing, and particularly to

Figs. 1 and 2 thereof, I show a clamp 10 constructed in accordance with my invention and including a first clamping member 11 which is connected by adjusting means 12 to a second clamping member 13. The first and second clamping members 11 and 13 are adapted to maintain a plurality of articles 14, such as planks, sheets of plastic or fiberboard, in superimposed relationship to facilitate the simultaneous operation thereupon of a tool, such as a bandsaw.

The first clamping member 11 is constituted by a rigid, elongated, substantially rectangular plate 16, as best shown in Fig. 3 of the drawing, the under side of the plate 16 being adapted to contact the upper surface of the uppermost of the pile of superimposed articles 14 when they are placed in the clamp 10. A first opening 17 is provided in the plate 16 intermediate the ends thereof while a second opening 18 is provided in the plate adjacent an end thereof and spaced from the first opening 17.

The second clamping member 13 is, as best shown in Figs. 1 and 4 of the drawing, constituted by a plate 20 which is very thin and which, in the present embodiment of my invention, is formed of a strip of spring steel stock $\frac{3}{32}$ inch in thickness. In the use of clamps constructed in accordance with my invention, I have discovered that the maximum thickness of the second clamping member 13 cannot be more than $\frac{1}{8}$ inch, for reasons which will be given in greater detail below. Since the plate 20 constituting the second clamping member 13 is formed of spring steel stock, it is resilient and any deflection occasioned therein when the articles 14 are clamped between the first and second clamping members is eliminated when the second clamping member is placed upon the table 22 of a bandsaw 23.

In conventional clamps the second clamping member 13 would be equivalent in thickness to the first clamping member 11 and when placed upon the surface of the table 22 of the bandsaw 23 the articles 14 disposed in a conventional clamp would have their vertical axes angularly disposed, as along a line B—B, with reference to a vertical axis A—A perpendicular to the surface of the table 22, as best shown in Fig. 1 of the drawing. The inclination from the vertical axes of the articles occasioned by the use of conventional clamps is attributable to the fact that the thickness of the second clamping members of such conventional clamps raises the under surface of the lowermost of the articles held in superimposed relationship by such a clamp above the surface of the table upon which the clamp is placed, causing those portions of the articles disposed in the clamp which are most remote therefrom to contact the surface of the table, said portions being lower than those portions of the articles which are retained in the clamp. Therefore, an angular disposition of the articles clamped with reference to the surface of the table results. When the articles are thus angularly disposed with reference to the surface of the table, simultaneous cuts made therein by the blade of the bandsaw will be angular rather than vertical and the purpose of simultaneously cutting the superimposed articles will be defeated, in that the cuts in the articles will not be identical.

By the use of applicant's clamp the possibility of the divergence of the vertical axes of the superimposed articles 14 from a vertical axis normal to the surface of the table 22 is eliminated, as best shown in Fig. 1 of the drawing. The extreme thinness of the second clamping member

13 engaging the under surface of the lowermost of the superimposed articles 14 prevents the under surface of the lowermost of the articles 14 from being raised a substantial distance above the surface of the table 22 and, by a slight pressure of the hands of the operator upon the portions of the superimposed articles adjacent the clamp 10 the deviation of the vertical axes of the superimposed articles 14 can be prevented, thus resulting in straight cuts or holes being formed in the superimposed articles.

Fastened to the upper surface of the resilient plate 20 which constitutes the second clamping member 13 is a rigid block 27, said block being secured to said upper surface by means of welds 28. The rigid block 27 acts as a stiffener for a substantial portion of the resilient plate 20 and has formed therein a first opening 29 and a second opening 30 spaced from said first opening 29.

The adjusting means 12 includes a first post 32, the lower end of which is disposed in the first opening 29 in the rigid block 27 and which is secured therein by means of welding or any other method of fastening. The upper end of the first post 32 is threaded, a wing nut 33 engaging said upper end of the post 32 and contacting the upper surface of the plate 16 constituting the first clamping member 11 adjacent the periphery of the first opening 17 in said plate, the upper end of said first post passing through said first opening.

A compression spring 34 encompasses the periphery of the lower portion of the first post 32, having its lowermost end seated on the upper surface of the rigid block 27 and its upper end engaging the lower end of a longitudinally shiftable collar 35 which surrounds the first post 32 and has its upper end biased against the under side of the first clamping member 11 adjacent the periphery of the opening 17 formed therein. Thus, the compression spring 34 continually urges the longitudinally shiftable collar 35 against the under surface of the first clamping member 11 and maintains said clamping member in contact with the wing nut 33. A second post 37 has its lower end seated in the opening 30 in the rigid block 27 and secured therein by means of a weld, its upper end being threaded and protruding through the second opening 18 in the first clamping member 11. A nut 38 engages the threaded upper end of the second post 37 and contacts the under side of the first clamping member 11 adjacent the periphery of the second opening 18 to support said first clamping member 11 adjacent said opening.

The clamp 10 is adjusted in the following manner: the second clamping member 13 is disposed in contact with the surface of the table 22 and the articles 14 are disposed in the space between the first and second clamping members. The wing nut 33 is then rotated to shift it in the proper direction to bring the under surface of the first clamping member 11 in contact with the upper surface of the uppermost of the articles 14 against the bias of the compression spring 34. The nut 38 on the second post 37 is then adjusted to maintain the first clamping member in a plane substantially parallel with the plane of the second clamping member 13.

When the upper clamping member 11 is adjusted through the action of the thumbscrew 33 to cause the under surface of the upper clamping member to engage the upper surface of the uppermost of the articles 14, those portions of the articles 14 disposed in the space between the first

and second clamping members 11 and 13 are compressed to secure them firmly in the clamp 10. However, since the second clamping member 13 is formed of light gage and readily deformable material, the compressive force exerted by the first clamping member 11 is, to a certain extent, exerted upon the surface of the table 22 of the bandsaw 23. Thus, when the articles 14 are cut, drilled or otherwise operated upon by a tool, the downward pressure exerted upon the articles by the operator of the tool serves, to a certain extent, to maintain the articles within the grip of the clamp 10.

I thus provide by my invention a clamp adapted to maintain a plurality of articles in superimposed relationship to facilitate the simultaneous operation thereupon of a tool, the clamp including a first, rigid clamping member and a second, deformable clamping member formed of light gage stock. By providing a second clamping member of very light gage, I prevent the divergence of the vertical axes of the superimposed articles from a vertical axis normal to the surface of the work table upon which the clamp and the articles secured therein are positioned.

I claim as my invention:

1. In a clamp adapted to maintain a plurality of articles in superimposed relationship on a table to permit the simultaneous operation of a tool thereupon, the combination of: a first clamping member; adjustment means connected to said first clamping member; a second clamping member; and a rigid block secured to the upper surface of said second clamping member for receiving said adjustment means to permit the adjustment of said first and second clamping members toward and away from each other, said second clamping member being deformable and thin to prevent the substantial inclination of the vertical axes of said articles from an axis perpendicular to the plane of said table.

2. In a clamp adapted to maintain a plurality of articles in superimposed relationship on a table to permit the simultaneous operation of a tool thereupon, the combination of: a first clamping member; adjustment means connected

to said first clamping member; a second clamping member; and a rigid block secured to the upper surface of said second clamping member for receiving said adjustment means to permit the adjustment of said first and second clamping members toward and away from each other, said second clamping member being resilient and thin to prevent the substantial inclination of the vertical axes of said articles from an axis perpendicular to the plane of said table.

3. In a clamp adapted to maintain a plurality of articles in superimposed relationship on a table to permit the simultaneous operation of a tool thereupon, the combination of: a first, rigid, elongated clamping plate of substantially rectangular cross section having forward and rearward free ends and being provided with a first, intermediate opening and a second, outermost opening adjacent one of said ends; a second, resilient clamping plate disposed below said first clamping plate; a rigid block secured to the upper surface of said second plate adjacent one end thereof; a vertical adjustment post secured at its lower end to said block, said adjustment post engaging said first opening in said first plate; and a vertical alignment post secured at its lower end to said block, said alignment post engaging said second opening in said first plate.
